UNITED STATES PATENT OFFICE.

JOSEPH JOHN NELIS, OF BROOKLYN, NEW YORK, ASSIGNOR TO FOSTER WHEELER CORPORATION, OF NEW YORK, N. Y., A CORPORATION OF NEW YORK.

MARINE STEAM-GENERATING UNIT.

Application filed May 10, 1923. Serial No. 637,997.

My present invention consists in a steam generating unit comprising a water tube boiler, an economizer and a superheater constructed and combined in a novel manner with the object of providing an efficient and durable unit adapted to satisfy the restricted space requirements, and the severe operating conditions to which ships' boilers are ordinarily subjected.

10 In carrying out my invention I combine a boiler of the inclined water tube cross drum type with an economizer above the boiler tubes, and with a superheater suitably incorporated in the wall of the furnace chamber, 15 and receiving its heat by radiation from the furnace chamber. With this combination I am enabled to obtain a desirably high overall efficiency and improved furnace chamber conditions, and to prolong the life of the 20 boiler furnace walls, with apparatus which, because of its compactness and structural characteristics, is well adapted for marine service. The economizer which I prefer to employ, while especially adapted for use in 25 the above mentioned combination comprises novel features of general utility.

The various features of novelty which characterize my invention are pointed out with particularity in the claims annexed to 30 and forming a part of this specification. For a better understanding of my invention, however, reference should be had to the accompanying drawings and descriptive matter in which I have illustrated and 35 described preferred embodiments of my invention.

Of the drawings:

Fig. 1 is an elevation in section;

40 Fig. 2 is a section on the line 2—2 of Fig. 1;

Fig. 3 is a partial section on the line 3—3 of Fig. 1; and

Fig. 4 is a longitudinal section of a portion of an economizer tube.

45 The boiler shown in the drawings comprises front and rear headers A' and A², connected by a bank of straight water tubes A³. The tubes A³ are inclined and the rear header A² is higher than the front header.

50 A cross steam and water drum A⁴, is connected to the front header A' by nipples A⁵, and is connected to the rear header A² by circulating tubes A⁶, which extend horizontally from the drum and have upwardly 55 inclined portions adjacent the rear header

A². Suitable baffles B advantageously formed of steel, insure the proper distribution of flow and length of gas passage for the heating gases passing upward through the inter-tube space of the boiler from the boiler furnace combustion chamber C. The boiler may be coal fired or oil fired. As shown it is heated by oil burners X mounted in the front wall of the combustion chamber.

60 The superheater G which I employ, is incorporated in the combustion chamber wall at the rear of the chamber C immediately beneath the elevated rear header A², and is of the type comprising a sectional metallic structure having its inner surface exposed 65 to the interior of the furnace chamber and receiving heat by radiation therefrom and conducting the heat so absorbed to the steam flowing through channels in the structure. In the construction illustrated, the steam 70 flows through tubes g having vertical body portions and transverse end portions g' which are connected to the superheater inlet header H and outlet header HA. The vertical bodies of the tubes g are encased in 75 cast iron blocks g² the smooth inner faces of which are exposed to the interior of the combustion chamber and absorb radiant heat from the burning gases in that chamber and from the side, bottom and front walls 80 of the chamber. In some cases a row of so-called shadow bricks g³ may be interposed 85 as shown between adjacent pairs of superheater elements. The bricks g³ project into the furnace chamber past the inner faces of 90 the blocks g² and restrict the radiant heat absorption of the latter somewhat. The superheater casing blocks g², or some of them, are advantageously connected to a metallic 95 framework G' which serves to support the superheater and to preserve the alignment of the superheater tubes, and may also serve to carry a portion of the weight of the boiler and boiler housing above the superheater.

100 The side, bottom and front end walls of the furnace chamber are lined with fire brick D and the boiler and furnace housing is advantageously encased in a sheet metal sheathing F to prevent air leakage. A suitable insulating material E is preferably interposed between the fire-brick lining D and the sheathing and is also interposed between the superheater G and the adjacent portion 105 of the sheathing. G³ is a superheater drain.

110 The economizer K, which is mounted

above the water tubes comprises a bank of horizontally disposed tubes K' which extend transversely to the water tubes and pass through a box-like casing K^2 formed of 5 metal plates and open at one end K^3 to receive the heating gases from the boiler and open at its opposite end K^4 to pass the gases to the stack. The economizer tubes are advantageously formed, as shown in Fig. 4, of 10 steel tubes encased in tubular and externally corrugated cast iron sections being thus similar in construction to the tubular elements employed in the well known Foster superheater.

15 In the preferred construction illustrated, the economizer is supported on transverse beams R and is located immediately above a flat roof portion A^7 of the boiler housing which is immediately above the horizontal 20 portions of the circulating tubes A^6 , and at a level appreciably below the top of the steam and water drum. The boiler housing comprises a box-like portion A^8 at the rear end of the boiler, which projects upward along- 25 side the inlet end of the economizer K , and is formed with an outlet for the heating gases communicating directly with the gas inlet K^3 of the economizer. The economizer as shown is flattened, its horizontal dimensions parallel and transverse to the tubes K' being each substantially greater than the vertical dimension of the economizer. The 30 economizer casing proper is covered with insulating material encased in a metal sheath- 35 ing forming in effect, an extension of the boiler housing sheathing F .

The economizer tubes are closely spaced and arranged in vertical rows with the tubes in adjacent rows staggered. The tubes in 40 the row adjacent the casing end K^4 are each connected at one end to the feed water inlet header L , and the tubes in the row at the opposite end of the economizer are each connected at one end to the outlet chamber LA 45 from which the heated feed water passes to the drum A^4 through the boiler feed pipe M . The economizer tubes in each intermediate row are connected to the tubes in an adjacent row at one side of the econo- 50 mizer by headers or connectors L' , and are connected at the other side of the economizer to the tubes of the other adjacent row by headers or connectors L^2 . K^6 represents a tube sheet extending across the bank of tubes 55 midway between the ends of the economizer.

Spray pipes O are located in the casing K^2 above the bank of economizer tubes. As shown these spray pipes are parallel to the economizer tubes and are spaced at regular 60 intervals along the length of the economizer and each extends across the economizer casing. Each adjacent pair of pipes O are connected to a separate water supply pipe O' , so that the economizer may readily be 65 cleaned in sections by successively supplying

water to the different pairs of spray pipes. With economizer tubes of the character described and arranged in vertical rows as shown, the water flowing down over each upper tube falls on to the tube immediately beneath it, so that the wash water supplied to each section does not spread to other sections. By washing the economizer in sections undue cooling of the economizer as a whole is avoided, and less disturbance in the 70 operation of the economizer is caused than would occur if the whole economizer was washed at the same time. The bottom of the economizer casing is shaped to form a 75 sort of a well beneath the bank of economizer tubes to receive the wash water which, with the soot or other furnace dust washed off the tubes, may be removed from the economizer housing through the drain pipe connections P . The cleaning of the economizer 80 tubes from time to time, enables a high economizer efficiency to be maintained.

85 Spaces are provided in the economizer casing above and below the bank of tubes to receive the spray pipes O and permit the proper discharge of water therefrom onto the adjacent portions of the tube bank, and to receive the wash water dripping from the tubes. To prevent the heating gases from 90 flowing through these spaces top and bottom baffles Q and Q' , respectively, are employed. These baffles are vertically disposed plates 95 extending parallel to the economizer tubes. The top baffles Q parallel and extending downward from the top wall of the economizer housing and the bottom baffles Q' extend down toward, but not quite into contact 100 with the bottom portion of the economizer casing. Advantageously each of these baffles has its edge adjacent the bank of tubes 105 extending into a corresponding one of the indentations formed in the top and bottom of the bank as a result of the arrangement 110 of the tubes in vertical rows with the tubes in adjacent rows staggered.

115 The economizer construction disclosed, while especially devised and adapted for use in the relation shown, is well adapted for use wherever it is desirable to have the heating gases flow horizontally through an economizer. The steam generating unit, as a 120 whole possesses important practical advantages for use under the severe conditions to which marine boilers are normally subjected. The available space for such boilers is extremely restricted, and the ratio of steam generated per unit of volume of space occupied must be relatively high. The available head room, or vertical distance from 125 top to bottom of the space available for the unit, is practically standard in most ships, and substantially less than that ordinarily occupied by units of similar capacity in land service. In consequence it is a practically universal rule in marine boiler furnaces, to 130

provide less combustion chamber volume than is provided in the furnaces of land boilers of similar capacity. Because of this decreased volume of combustion chamber space and the fact that the load on marine boilers is normally maintained approximately constant, and near the practical maximum capacity of the boilers throughout the time required for a ship to make a trip, marine boiler furnace walls tend to deteriorate more rapidly than do the corresponding walls of land boilers in which heavy load periods commonly alternate with light or no load periods. Marine boilers are ordinarily so housed and operated under such draft, moreover, that their walls are not protected against overheating by the slow infiltration of air as is commonly the case with land boiler furnaces.

With the present invention the entire rear wall of the combustion chamber is directly cooled by the superheater incorporated therein. In addition, the absorption of heat by the superheater, lowers the furnace chamber temperature, and cools the side, bottom and front end walls of the combustion chamber so that the superheater prolongs the life of all portions of the wall of the combustion chamber. In the arrangement disclosed, the superheater and the water tubes form radiant heat absorbing black bodies, which in a degree oppose one another, and jointly absorb a large amount of radiant heat from the furnace chamber and cool all the walls thereto. The radiant heat absorption by the bank of water tubes is augmented by the open spacing of the water tubes in the lower rows of the bank of tubes, which exposes substantial portions of the surfaces of tubes above the lower row of water tubes to radiant heat.

The reduction in furnace chamber temperature produced by the superheater, reduces the volume of the furnace gases and thus reduces the combustion chamber volume required for a given combustion capacity and efficiency. The invention also permits of a direct increase in combustion chamber volume by elongating the boiler, as compared with the practice heretofore standard, since with the radiant heat absorbed by the superheater, and the absorption of heat from the gases leaving the boiler by the economizer, the temperature of the gases leaving the economizer can be kept sufficiently low with a bank of water tubes which is relatively small in a vertical direction, and is increased horizontally to secure the required amount of boiler heating surface.

The type of economizer employed, by reason of its shape, and the character and close spacing of the economizer tubes, permits of an adequate amount of economizer heating surface in an economizer requiring a relatively small amount of head room. While

the exact form and proportion of the parts, and the size of the units are not essential features of the invention, it may facilitate a proper appreciation of the invention and its practical importance, to note the fact that a particular installation, of the form and relative proportions illustrated in the drawings, in which the total vertical distance from the bottom surface of the economizer casing is approximately sixteen and one half feet, was designed to, and is capable of generating steam economically and continuously at the rate of 16,000 lbs. per hour, at 250 lbs. pressure, and imparting 150° or more of superheat to the steam generated and can carry much heavier loads when occasion requires.

While in accordance with the provisions of the statutes, I have illustrated and described the best forms of my invention now known to me, it will be apparent to those skilled in the art that many changes may be made in the form of the apparatus disclosed without departing from the spirit of my invention as set forth in the appended claims, and that certain features of my invention may sometimes be used with advantage without a corresponding use of other features.

Having now described my invention, what I claim as new and desire to secure by Letters Patent, is:

1. A marine boiler comprising a combustion chamber, a bank of water tubes above said combustion chamber, upper and lower headers connected to said tubes, a steam and water drum above said lower header and extending transversely to said tubes, tube connections between said drum and headers, a radiant heat superheater incorporated in a wall of said combustion chamber and adapted to absorb radiant heat from the other walls of said chamber and an economizer located above said water tubes and the tube connections between the upper header and drum.

2. A marine boiler comprising a combustion chamber, a bank of inclined water tubes above said combustion chamber, upper and lower headers connected to said tubes, a steam and water drum above said lower header and extending transversely of said tubes, tube connections between said drum and headers, a radiant superheater incorporated in the high end wall of said combustion chamber and adapted to absorb radiant heat from the other walls of said chamber and an economizer located above said water tubes and the tube connections between the upper header and drum.

3. A marine boiler comprising a combustion chamber, a bank of inclined water tubes above said combustion chamber, upper and lower headers connected to said tubes, a steam and water drum above said lower

- header and extending transversely of said tubes, tube connections between said drum and headers, a radiant heat superheater incorporated in a wall of said combustion chamber and adapted to absorb radiant heat from the other walls of said chamber, a bank of horizontal economizer tubes extending transversely of said water tubes located above said tube connections between the upper header and drum and a casing enclosing said economizer tube bank having a heating gas inlet at one side and a heating gas outlet at the opposite side of said bank of tubes.
15. 4. The combination with a horizontal water tube boiler comprising upper and lower headers connected by the water tubes and a cross steam and water drum above the lower header, of an economizer located above the water tubes, and comprising a bank of horizontal tubes transverse to the water tubes and a casing enclosing said bank and extending downward into the space between the higher header and said drum with an inlet for heating gases from the boiler at one side of the bank and an outlet for heating gases at the other side of said bank.
5. The combination with a water tube boiler comprising upper and lower headers connected by the water tubes and a cross steam and water drum above the lower header, of an economizer above the water tubes and comprising a bank of horizontal tubes transverse to the water tubes and a casing enclosing said bank of tubes and extending down into the space between the higher header and said drum, and a housing for the boiler comprising a portion extending upward alongside the economizer casing and communicating therewith through a port at one side of said bank of tubes.
6. An economizer comprising a bank of horizontal tubes and a casing traversed by said tubes and provided with a heating gas inlet at one side, and a heating gas outlet at the opposite side of the tube bank, and spaced away from the top and bottom of the bank, means located in the space above the bank for discharging cleaning water onto the bank of tubes, drain connections from the space at the bottom of the bank, and baffles parallel to the water tubes in the spaces above and below the bank of water tubes restricting flow of the heating gases through said spaces.
7. An economizer comprising a bank of horizontal tubes and a casing traversed by said tubes and provided with a heating gas inlet at one side, and a heating gas outlet at the opposite side of the bank and spaced away from the top and bottom of the bank, water spray pipes located in the space above the bank and extending parallel to the econ-
- omizer tubes, drain connections from the space at the bottom of the bank, and baffles parallel to the water tubes in the spaces above and below the bank of water tubes restricting flow of the heating gases through said spaces.
8. An economizer comprising a bank of horizontal tubes and cleaning means therefore comprising spray pipes parallel to said tubes arranged above said bank at horizontally spaced apart intervals, and separate water supply connections to said pipes whereby different sections of the bank may be washed at different times.
9. An economizer comprising a bank of horizontal tubes arranged in rows with the tubes in adjacent rows staggered whereby indentations are formed in the top surface of said bank, a casing enclosing said tubes and formed with a heating gas inlet at one side and a heating gas outlet at the opposite side of the bank and spaced away from the top of the bank, baffles parallel to the tubes extending downward from the top of the casing into corresponding indentations in the top of the bank, and means located in the space above the tube bank for spraying wash water on to the tubes.
10. An economizer comprising a bank of horizontal tubes arranged in rows with the tubes in adjacent rows staggered whereby indentations are formed in the top of said bank, a casing enclosing said tubes and formed with a heating gas inlet at one side and a heating gas outlet at the opposite side of the bank and spaced away from the top of the bank, baffles parallel to the tubes extending downward from the top of the casing into corresponding indentations in the top of the bank, and means for spraying wash water on to the tubes comprising spray pipes parallel to said tubes and located in the space above the tubes at the sides of said baffles.
11. An economizer comprising a bank of horizontal tubes arranged in staggered rows whereby indentations are formed at the bottom of the bank, a casing enclosing said bank and provided with a heating gas inlet at one side and a heating gas outlet at the opposite side of the bank, and spaced away from the bottom of the bank to receive wash water draining off the tubes, means for spraying wash water on to the top of the bank of tubes, and baffles parallel to the tubes and having their upper edges extending into corresponding indentations in the lower side of the bank for restricting flow of the heating gases through said space.

Signed at New York city, in the county of New York and State of New York, this 8th day of May, A. D. 1923.

JOSEPH JOHN NELIS.
